United States Patent

Des. 239,632
Patented Apr. 20, 1976

239,632

SNAFFLE BIT

Albert E. Ostermaier, 11138 Aqua Vista,
North Hollywood, Calif. 91603

Filed June 7, 1974, Ser. No. 477,232

Term of patent 14 years

Int. Cl. D30—04

U.S. Cl. D30—21

Fig. 1.

Fig. 2.

Fig. 3.

FIG. 1 is a front elevational view of a snaffle bit showing my new design;

FIG. 2 is a top plan view; and

FIG. 3 is a side elevational view.

I claim:

The ornamental design for a snaffle bit, substantially as shown.
